(57) **CLAIM**

The ornamental design for the adjustable shelf, as shown and described.

DESCRIPTION

FIG. 1 is an exploded perspective top front view of the adjustable shelf of the present invention;

FIG. 2 is an exploded perspective bottom front view of the present invention;

FIG. 3 is a perspective top view of the present invention in collapsed form;

FIG. 4 is a perspective bottom view of the present invention in collapsed form;

FIG. 5 is a top side view of the present invention in collapsed form;

FIG. 6 is a bottom side view of the present invention in collapsed form;

FIG. 7 is a front side view of the present invention in collapsed form;

FIG. 8 is a back side view of the present invention in collapsed form;

FIG. 9 is a right side view of the present invention in collapsed form;

FIG. 10 is a left side view of the present invention in collapsed form;

FIG. 11 is a top perspective view of the present invention in expanded form;

FIG. 12 is a bottom perspective view of the present invention in expanded form;

FIG. 13 is a top side view of the present invention in expanded form;

FIG. 14 is a bottom side view of the present invention in expanded form;

FIG. 15 is a front side view of the present invention in expanded form;

FIG. 16 is a back side view of the present invention in expanded form;

FIG. 17 is a right side view of the present invention in expanded form; and,

FIG. 18 is a left side view of the present invention in expanded form.

(Continued)

The broken lines illustrate portions of the adjustable shelf that form no part of the claimed design.

1 Claim, 18 Drawing Sheets

Related U.S. Application Data

No. 29/769,945, filed on Feb. 8, 2021, now Pat. No. Des. 933,404, which is a continuation-in-part of application No. 29/754,701, filed on Oct. 13, 2020, now abandoned, which is a continuation of application No. 29/689,053, filed on Apr. 26, 2019, now Pat. No. Des. 898,489.
